UNITED STATES PATENT OFFICE.

GEORGE D. HECK, OF PRINCE BAY, NEW YORK, ASSIGNOR TO THE S. S. WHITE DENTAL MANUFACTURING COMPANY, A CORPORATION OF PENNSYLVANIA.

DENTAL CHAIR.

Application filed March 27, 1923. Serial No. 627,966.

My invention relates particularly to foot-rests for dental chairs, and is especially directed to that class of foot-rests in which the foot-rest frame is carried by the chair frame, and has a toe-board frame hingedly mounted on said foot-rest frame, and arranged to be swung thereon toward and from the chair seat.

The principal objects of my invention are to provide a dental chair with a foot-rest having a toe-board so hingedly connected therewith as to be swung thereon toward and from the chair seat with minimum effort on the part of the operator and without inconvenience to the patient in the chair.

Other objects of my invention are to provide a dental chair with the foot-rest having a toe-board arranged to be automatically retained in a plane with the foot-board, or in inclined relation therewith, and to be adjusted to either position by a mere lifting movement of the toe of the operator.

Further objects of my invention are to provide a foot-rest so constructed and arranged that the foot-board and toe-board may be securely engaged with their respective frames, yet be readily removed and replaced.

Specifically stated, the form of my invention, as hereinafter described, comprehends a foot-rest frame carrying a foot-board, and a toe-board frame pivoted thereto and carrying a toe-board, a notched lever actuated by gravity and tending to automatically retain said toe-board frame in its respective positions, and arranged to be raised by the toe of the operator to release said toe-board frame when inclined, and to automatically release said toe-board frame when said toe-board frame is raised from its horizontal position, by the toe of the operator. The foot-board and toe-board, which may be cut pieces of linoleum or similar sheet material, rest on their respective frames upon plates from which the perimetric margins have been removed and formed into retaining rims arranged to overlie and engage the margins of said boards and to rigidly secure them to their respective frames.

My invention also includes all of the various novel features of construction and arrangement as hereinafter more definitely specified.

In the accompanying drawings Figure 1 is a plan view of a foot-rest constructed in

accordance with my invention, showing portions of the foot-board and toe-board broken away for convenience of illustration; Fig. 2 is a side elevational view of the foot-rest shown in Fig. 1, portions being broken away for convenience of illustration; Fig. 3 is a vertical, longitudinal, sectional view of the foot-rest shown in Figs. 1 and 2, with the toe-board frame raised to its inclined position, and its retaining lever shown in elevation; Fig. 4 is a transverse vertical sectional view taken on the line 4-4 in Fig. 1; and Fig. 5 is a fragmentary, transverse, vertical sectional view taken on the line 5-5 in Fig. 1.

In said figures, the foot-rest, which may be conveniently supported in a well-known manner by the chair frame, of which the depending brackets 1 and 2 are shown, comprises the foot-board frame 3 and toe-board frame 4 hingedly connected for relative adjustment. The foot-board frame may preferably be formed of the longitudinally ribbed side rails 5 and 6 and the transverse connecting rails 7 and 8 all of which may be channeled to provide lightness to the structure, which is stiffened by the longitudinally disposed brace beam 9, having the supporting saddle 10.

The forward rail 8 of the foot-board frame 3 is provided with forwardly extending hinge lugs 11, to which the hinge lugs 12 of the toe-board frame 4, comprising the side rails 13 and 14 and the transverse rails 15 and 16, which may be channeled, are hingedly connected by the shaft 17.

The foot-board frame 3 is arranged to be rigidly connected in a well-known manner with the chair frame comprising the brackets 1 and 2, and the toe-board frame is arranged to be held in two positions with respect to the foot-board frame; one of said positions being disposed in a plane with the foot-board frame, as shown in Fig. 2, and the other position being relatively inclined thereto, as shown in Fig. 3.

The toe-board frame is arranged to be supported in its respective positions by the lever 19, comprising a rectangular structure having the side-bars 20 and 21 joined by the transversely disposed connecting bars 22 and 23. Said lever 19 is conveniently mounted for oscillation upon the rock shaft 25, which is supported in suitably formed bearings 26 and 27 respectively in the brace 110

beam 9, and side rail 6, and which is arranged to be held stationary in its bearings by the set screw 28 in the bearing 26.

The side bar 21 of said lever 19 is extended forwardly and terminates in a pedal 29 disposed beneath the toe-board frame 4, and the side bar 20 is provided with the bearing 30 for the hollow shaft 33 which carries the links 32 connecting said lever 19 with the shaft 34 mounted in the shaft bearing brackets 35, which depend from the back rail 15 of the toe-board frame 4.

The shaft 34 may be conveniently provided with the rotatable sleeve or roller 36, which is arranged to alternately engage the recesses 38 and 39 in the under side of the side-bar 20 of the lever 19, to maintain the toe-board frame 4 respectively in alinement with the foot-board frame or inclined thereto. Said lever 19 carries a spring 40, which loops into the recess 38 and closely hugs the under surface of the bearing 30 and upon which the roller 36 rides into its loop, so as to prevent undue shock or jar when the toe-board frame is released and permitted to drop to its horizontal position shown in Fig. 2.

The upper surface 41 of the inner wall of the channeled foot-board frame 3 is slightly lower than the upper surface 42 of the outer wall of said frame, and affords a support for the foot-board reinforcing plate 43, upon which the foot-board 44 rests with its margin overlying the surface 42 of said frame, being rigidly engaged therewith by the marginal retaining rim 45. As best shown in Fig. 3, the reinforcing plate 43, and foot-board 44, which may be formed of linoleum or other suitable material, are supported centrally by the supporting saddle 10.

The retaining rim 45 as best shown in Fig. 5, is arranged to overlie the margin of the foot-board 44, and has the web of its lateral bars 46 and 47 extended downwardly and inwardly to embrace the outwardly projecting flanges 49 and 50 of the side rails 5 and 6 respectively of the foot-board frame. The lower inwardly directed webs 52 and 53 of the lateral bars 46 and 47 are provided with set screws 55 in threaded engagement therewith, arranged to bear against the under surface of said flanges 49 and 50, to tightly engage the retaining rim 45 with the margin of the foot-board 44, and clamp it upon the upper surface 42 of the foot-board frame 3.

Similar to the foot-board frame, the toe-board frame is provided with the plate 57 arranged to reinforce the toe-board 59, which may be formed of sheet material such as linoleum or other suitable composition, and which is held thereon by the marginal retaining rim 60, the webs of whose forward bar 61 and lateral bars 62 and 63 are extended downwardly and inwardly to embrace the flange 65, projecting outwardly

from the forward and lateral bars respectively of the toe-board frame. The lower inwardly directed web 69 of the retaining rim 60 is provided with set screws 70 in threaded engagement therewith and arranged to bear against the under surface of the flange 65 to tightly engage the retaining rim 60 with the margin of the toe-board 59, and thereby clamp it upon the upper marginal surface 72 of said toe-board frame. The rim 60 is extended rearwardly to provide an apron 73 which bridges the gap between the foot-board and toe-board and conveniently covers the hinge shaft 17.

It will be obvious that the toe-board may be readily removed and replaced by backing the set screws 70, which permits the retaining rim 60 to be easily drawn forwardly from its engagement with the flange 65, thereby leaving the toe-board 59 free to be lifted from the toe-board frame 4; and similarly, the retaining rim 45 may be conveniently removed by backing the set screws 55, which permits said rim to be readily drawn forward over the toe-board frame when extended in alinement with the foot-board frame as shown in Figs. 1 and 2, thus leaving the foot-board 44 free to be lifted from the foot-board frame 3; the replacement of said parts being obviously effected in the reverse order.

It may be here noted that the reinforcing plates 43 and 57 may be formed of the included area of the material from which the retaining rims 45 and 60 are formed.

My invention is advantageous in that the toe-board frame is raised to its inclined position shown in Fig. 3 by an upward movement of the toe of the operator and may be released and permitted to drop to its horizontal position shown in Figs. 1 and 2 by a similar movement, in substantially the same position of the toe of the operator, to lift the pedal 29, which effects the release of said toe-board.

The operative adjustment of the toe-board is effected as follows.—If it is desired to raise the toe-board from its horizontal position shown in Fig. 2 to its inclined position shown in Fig. 3, the operator places his toe under the toe-board frame, preferably toward its outer free end, and lifts it upward to the position shown in Fig. 3. Such movement of the toe-board frame causes the roller 36 to ride out of the recess 38 and upon the spring 40 into the recess 39; in so doing it causes the free end of the lever 19 to rise until said roller 36 passes the vertical plane of the axis of the shaft 33, whereupon said lever again descends as the roller 36 rides into the recess 39, against the wall of which it bears to support the toe-board frame in the inclined position shown. The return of the toe-board frame to the horizontal position may be similarly effected by the op-

erator placing his toe beneath the pedal 29 of the lever 19, and by lifting said pedal until the axis of the shaft 33 passes the horizontal plane of the axis of the roller 36, 5 when the weight of the toe-board being no longer supported by the wall of the recess 39, will force the roller backward to ride upon the spring 40 into the recess 38, wherein it bears against the wall of said recess to 10 support the toe-board frame in its horizontal position shown in Fig. 2.

I do not desire to limit my invention to the precise details of construction and arrangement as herein set forth, as it is obvious 15 that various modifications may be made therein without departing from the essential features of my invention as defined in the appended claims.

Having thus described my invention, I 20 claim:

1. A foot-rest comprising a foot-board frame and a toe-board frame hingedly connected with said foot-board frame, a pivoted lever actuated by gravity, provided with 25 separate recesses and having a linked connection with said toe-board frame, and means on said toe-board frame arranged to engage said recesses to retain the toe-board in different predetermined positions with respect to the foot-board.

2. A foot-rest comprising a foot-board frame and a toe-board frame hingedly connected with said foot-board frame, a lever having recesses therein, pivoted to said foot-board frame and extended forwardly, links connecting said lever with said toe-board frame, means on said toe-board frame arranged to engage said recesses to support said toe-board frame in different predetermined positions with respect to said foot-board frame, and yielding means arranged to absorb the shock incident to their relative adjustment.

3. A foot-rest comprising a foot-board frame and a toe-board frame hingedly connected with said foot-board frame, a lever pivoted to said foot-board frame, provided with recesses and having a pedal extended beneath said toe-board frame, and means on

said toe-board frame arranged to engage 56 said recesses to maintain said toe-board frame in different positions with respect to said foot-board frame, the upward adjustment of said toe-board frame and its release being effected by a similar upward movement of the toe of the operator, respectively 61 with said toe-board frame and with said lever.

4. A foot-rest comprising a foot-board frame and a toe-board frame hingedly connected with said foot-board frame, a lever pivoted to said foot-board frame provided with recesses and having a pedal extended beneath said toe-board frame, links connecting said lever with said toe-board frame, and means on said toe-board frame arranged to engage said recesses to maintain said toe-board frame in different predetermined positions, the adjustment of said toe-board frame to its inclined position and its release therefrom, being effected by a similar upward movement of the toe of the operator, respectively 65 with said toe-board frame and with said lever.

5. A foot-rest comprising a foot-board frame and a toe-board frame hingedly connected with said foot-board frame, a lever actuated by gravity, pivoted to said foot-board frame, provided with indentations and having a pedal extended beneath said toe-board frame, links connecting said lever with said toe-board frame, means on said toe-board frame arranged to engage said indentations to maintain the toe-board frame in different predetermined positions, and a 75 spring arranged to absorb the shock incident to the adjustment of said toe-board frame with respect to said foot-board frame, the upward adjustment of said toe-board frame being effected by an upward movement of 80 the toe of the operator thereunder and its release being effected by a similar movement of the toe of the operator against the pedal of said lever.

In witness whereof, I have hereunto set 85 my hand this 9th day of March, A. D. 1923.

GEORGE D. HECK.
